UNITED STATES PATENT OFFICE.

DOMENICO BRUNELLI, OF PHILADELPHIA, PENNSYLVANIA.

DESIGN FOR AN ACOUSTIC CABINET.

Application filed January 31, 1923. Serial No. 5,037. Term of patent 7 years.

To all whom it may concern:

Be it known that I, DOMENICO BRUNELLI, a subject of the King of Italy, residing at Philadelphia, in the county of Philadelphia and State of Pennsylvania, have invented a new, original, and ornamental Design for Acoustic Cabinets, of which the following is a specification, reference being had to the

accompanying drawing, forming part thereof.

The figure is a perspective view of a cabinet, showing my new design.

I claim:

The ornamental design for an acoustic cabinet, as shown.

DOMENICO BRUNELLI.
